(57) **CLAIM**

The ornamental design for a fabric pouch carry accessory for a mobile phone device, as shown and described.

DESCRIPTION

FIG. 1 is a perspective view of a fabric pouch carry accessory for a mobile phone device showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 depicts a back perspective view of the fabric pouch carry accessory for a mobile phone device, while carrying a headset.

The broken lines in FIG. 8 are provided to illustrate environment and form no part of the claimed design.
